UNITED STATES PATENT OFFICE.

JAMES A. PEEK, OF NORTH MANCHESTER, INDIANA, ASSIGNOR OF ONE-HALF TO CHAS. F. NOFTZGER AND JOHN S. ANDREWS, OF SAME PLACE.

HARVESTER.

SPECIFICATION forming part of Letters Patent No. 322,001, dated July 14, 1885.

Application filed August 14, 1883. Renewed December 19, 1884. (No model.)

To all whom it may concern:

Be it known that I, JAMES A. PEEK, a citizen of the United States, residing at North Manchester, in the county of Wabash and State of Indiana, have invented certain new and useful Improvements in Harvesters; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical cross-section taken through the friction-rollers. Fig. 2 is a vertical longitudinal section across the drive-wheel.

This invention has relation to harvesters; and it consists in the construction and novel arrangement of devices, as will be hereinafter fully described, and particularly pointed out in the claim.

Referring by letter to the accompanying drawings, *a* designates the drive-wheel of the machine, which is without either a hub or spokes, the rim *b* being provided with an internal flange, *c*, its edge being rounded in cross-section.

d indicates the frame of the harvester. It is provided with a frame, *i*, at one end, in which the bearings for the geared shafts *k* and *l* are formed on the under side thereof. The shafts *k* and *l* are connected by miter gear-wheels *m n* at right angles to each other, the shaft *l* being provided with a crank for driving the knife. The shaft *k* is provided with a fixed grooved friction-roller, *o*, located about centrally of the frame *i*, which roller engages the rounded flange *c*.

Arms *p p'* rise from the frame *i*. They are curved outwardly, and are connected at their upper ends by a bar, *q*. The bar *q* is perforated at *r r'* to receive the journals *s s'*, on which small grooved friction-rollers *t t'* revolve. These latter rollers also engage the annular flange *c* of the open drive-wheel and steady the wheel. The weight of the machine

comes mainly upon the single larger grooved friction-wheel *o* on the shaft *k*, and the motion is imparted to the knife by the friction produced between the flange of the drive-wheel and said roller *o*.

u designates the carrier, which may be of any approved construction, and arranged to carry the cut grain through the open drive-wheel to the grain-binder, which may be also of any well-known construction, or may be done by hand.

v indicates the grain-wheel at the outer end of the frame.

I am aware that it is not new to provide a harvester with a grain-passage through its drive-wheel, and that such a drive-wheel has been provided with an inner annular flange to operate a friction-pulley, the shaft from which operates the cutting apparatus, and therefore do not claim such construction, broadly; but,

Having thus fully described my invention, what I claim as new, and desire to secure by Letters Patent, is—

In a harvester, the combination of the frame *d*, the frame *i*, secured to said frame, the curved arms *p p'*, rising from the frame *i*, the bar *q*, connecting the upper ends of said arms, the friction-rollers *t t'*, journaled in the upper ends of said arms, the drive-wheel *a*, provided with the internal rounded flange, *c*, the shaft *k*, located centrally of the frame *i* and journaled beneath the same, the friction-roller *o*, fixed to said shaft and engaging with flange *c*, the beveled pinion *m*, also fixed to said shaft, the crank-shaft *l*, also journaled beneath the frame *i*, and provided with the bevel-pinion *n*, meshing with the pinion *m*, and having a crank for driving the cutter-bar, substantially as specified.

In testimony whereof I affix my signature in presence of two witnesses.

JAMES A. PEEK.
